(57) **CLAIM**

The ornamental design for a game board, as shown and described.

DESCRIPTION

The claimed game board is used for recreational game play. FIG. 1 is a top plan view of a game board, showing my new design, the bottom being plain and unornamented; FIG. 2 is a side elevation view thereof, the other sides being identical; and, FIG. 3 is an enlarged partial top plan view of the central region and of a typical rectangular region shown in FIG. 1, all rectangular regions being identical.
